UNITED STATES PATENT OFFICE.

JOHN BLAKE KELLOGG, OF ORANGE, NEW JERSEY.

VACUUM-CLEANER.

1,255,175.

Specification of Letters Patent.

Patented Feb. 5, 1918.

Application filed July 10, 1916. Serial No. 108,296.

To all whom it may concern:

Be it known that I, JOHN BLAKE KELLOGG, a citizen of the United States of America, and a resident of Orange, Essex county, 5 and State of New Jersey, have invented certain new and useful Improvements in Vacuum-Cleaners, of which the following is a specification, reference being had to the accompanying drawings, forming a part 10 thereof.

My invention relates to wall receptacles for suction cleaning apparatus and has for one object to provide a relatively small compact receptacle that shall be arranged and 15 adapted to receive the inner end of a flexible hose to which a cleaning tool is attached.

Another object is to provide a receptacle of the aforesaid character that shall automatically complete the circuit for the pump 20 motor of the system when the hose attachment is inserted therein.

In stationary vacuum cleaning apparatus, such as is installed in residences and other buildings, there are provided a plurality of 25 outlets to which the flexible hose may be connected. It has been my aim to produce a flush socket receptacle that shall be simple and attractive in appearance and which shall be adapted not only to receive the hose attachment but also shall be arranged to cooperate with an attachment of ordinary 30 character in completing an electric circuit to the pump motor of the apparatus. At the same time I have particularly aimed to 35 avoid the obstruction of the air passage or the complication of the structure.

In order that my invention may be thoroughly understood, I will now proceed to describe the same in the following specification, 40 and then point out the novel features thereof in appended claims.

Referring to the drawings:

Figure 1 is a partially sectional and partially diagrammatic elevation of vacuum 45 cleaning apparatus, comprising a wall socket or receptacle which embodies my invention.

Fig. 2 is a transverse sectional elevation of the wall socket shown in Fig. 1, drawn to a larger scale and taken on the line 2—2 of 50 Fig. 3.

Fig. 3 is a front elevation of the same receptacle with the cover removed.

Fig. 4 is a front elevation with the cover in position.

Fig. 5 is a diagrammatic view illustrating 55 the circuit connections for the system.

In the drawings,—10 represents the pump which is usually located in the basement; 11 is an electric driving motor therefor; 12 a main collecting pipe; 13 a branch therefrom, and 14 a receptacle or socket attached to the branch. A cleaning tool 15 is connected to the outer end of a flexible hose 16 which has an attachment 17 at its inner end to cooperate with the receptacle 14. 65

The receptacle 14 as shown more in detail in Figs. 2, 3 and 4, comprises a metal box 18, which is attached by means of screws 19 to a screw-threaded collar 20, a block 21 of insulation within the box, a socket composed 70 of metal terminal segments 22 and 23 and insulating segments 24, and a cover plate 25.

As shown diagrammatically in Fig. 1, the terminal contact members 22 and 23 are respectively connected to a supply line conductor 26 and a conductor 27 which is connected at 28 to one terminal of the motor 11. The other terminal 29 of the motor is connected to a line conductor 30. 75

The arrangement of parts is such that 80 when the attachment 17 is inserted in the socket, a circuit is established from conductor 30 through the motor windings, conductor 27 and terminals 23 and 22, which are bridged by the attachment 17, to conductor 26. 85

A cover plate 25 has an opening 32 which is adapted to be covered by a lid 33 which fits into the opening and when closed is flush with the outer surface of the plate or 90 cover 25. Attached to the lid 33 which is pivoted at 34 is a block or plate 35 of insulating material which engages, when the lid is closed, the outer end of the socket and protects the terminal members from a short 95 circuit.

Instead of closing the motor circuit directly, by means of the receptacle contacts, the arrangement of Fig. 5 may be employed in which a relay switch 36 is introduced in 100 the motor circuit 37. An auxiliary control circuit 38 is connected to one of the supply circuit conductors 40 and includes a magnet coil 41 for the relay switch. The circuit 38 also includes the contact terminals 22 and 105 23 of the receptacle.

The arrangement is such that the relay switch is open and the motor circuit inter-

rupted except when the terminal contacts 22 and 23 are bridged by the connector 17. In this event the branch circuit is completed, the relay switch closed, and the motor circuit established.

5 In either of the modifications shown and described the motor circuit is interrupted and the pump is inactive except when the flexible hose attachment is coupled to the 10 wall receptacle; then the motor circuit is completed, the pump automatically started and the cleaning process may be continued as long as desired. It will be stopped upon the removal of the attachment from the 15 socket.

Obviously, there will always be a number of receptacles provided in different parts of the residence or building in which the cleaning apparatus is installed.

20 Various structural modifications may be provided within the spirit and scope of my invention, and I intend that only such limitations be imposed as are indicated in the appended claims.

25 What I claim is:

1. A connector for vacuum cleaning apparatus comprising a casing adapted to be connected to an intake pipe, and formed to provide a socket communicating with the pipe, 30 a pair of electrically independent terminal contact members, and a hose attachment connector adapted to be inserted in the socket and adapted when inserted to complete electrical circuit between the contact members 35 and establish a fluid connection between the intake pipe and the hose.

2. A connector for vacuum cleaning apparatus comprising a metal box or casing adapted to be attached to an intake pipe, a 40 hollow insulating block within the box formed to provide a cylindrical socket constituting a continuation of the interior of the pipe, a pair of terminal contact members mechanically supported and electrically 45 separated by the insulating block, and a hose

connector adapted to be inserted in the socket, to complete electric circuit between the contact members and establish a fluid connection to the hose.

3. A connector for vacuum cleaning apparatus comprising a metal box or casing adapted to be attached to the intake end of a cleaning pipe, a hollow insulating block within the box formed to provide a cylindrical socket constituting a continuation of 50 the interior of the pipe, a pair of terminal contact members mounted on the insulating block and constituting spaced parts of the cylindrical socket, and a hose attachment adapted to be inserted in the socket to complete 55 electrical circuit between the contact members and to establish a fluid connection to the hose.

4. A connector for vacuum cleaning apparatus comprising a cleaning pipe, a casing 60 attached thereto, an insulating member in the casing, a socket communicating with the pipe and forming a part of the casing, a pair of electrically independent terminal contact members, and a hose attachment connector 65 adapted to be inserted in the socket to complete electrical circuit between the contact members and to establish a fluid connection between the intake pipe and the hose.

70 5. A connector for vacuum cleaning apparatus comprising a cleaning pipe, a metal box or casing attached to the intake end thereof, a hollow insulating block within the box formed to provide a cylindrical socket constituting a continuation of the interior of 75 the pipe, a pair of terminal contact members mounted on the insulating block and constituting spaced parts of the cylindrical socket, and a hose attachment adapted to be inserted in the socket to complete electrical circuit 80 between the contact members and to establish a fluid connection to the hose.

In witness whereof, I have hereunto set my hand this 6 day of July, 1916.

JOHN BLAKE KELLOGG.
